VENETIAN BLIND HEAD ENCLOSURE

Richard H. Wright, Bratenahl, Ohio, assignor to
The Guarantee Specialty Manufacturing Com-
pany, Cleveland, Ohio, a corporation

Application August 3, 1951, Serial No. 240,150

1 Claim. (Cl. 160—177)

1

This invention relates to Venetian blinds, and in particular to certain components thereof which are known as head enclosures.

Heretofore head enclosures for Venetian blinds have been made of metal and like substances, although not necessarily so, since the same may be made of wood also, the same being usually of substantially U-shaped configurations in cross section, and adapted to support therewithin the instrumentalities for operating the various parts of the blinds, and supporting the tapes and slats comprising the same in a window or like opening.

As is usually the case, such head enclosures or head bar units as above described, are of open construction and as such permit the accumulation of large quantities of dirt and dust, which eventually affect the operation of the parts enclosed within the head bar. Furthermore parts within the head bar are not generally accessible except by removing the blind as a whole from the window or other location, and therefore are not generally cleaned periodically as are other parts of the blind which are exposed.

Insofar as I am aware, it has not been heretofore proposed to provide a metal head bar unit of the class to which this invention is directed, which is fully enclosed, so as to exclude a substantial proportion of the dirt and dust ordinarily accumulated therein in other types of head enclosures.

It is therefore an object of this invention, to provide a head enclosure for Venetian blinds, which is fully enclosed and thereby exclude foreign matter from entrance thereto.

It is a further object of this invention to provide a simple construction of head enclosure, wherein the same may be readily accessible for replacement or repair of parts within the enclosure, and yet maintain the same in relatively dust-free condition.

It is a further object of this invention to provide a head enclosure which avails of commonly used parts to effect the complete enclosure, one of the parts used, comprising a metal slat, for example, such as is used in the blind itself. The type of slat used may similarly be a substantially concave type of slat or one which is rolled or otherwise formed so as to be concave in cross section.

A still further object of this invention is to so form the metal head enclosure body portion of the invention, so as to provide suitable grooves or other means for maintaining and supporting a cover such as the metal slat above referred to

2

therein. Such provision will enable the ready removal of and emplacement in the position for completing the enclosure either by suitable compression at the edges of the slat, or inserting the same from an end of the body of the enclosure.

Other and further objects of the invention will be understood from an explanation thereof, taken in conjunction with the drawing wherein:

Figure 1 is an end view of the enclosure of 10 the invention, showing certain operating parts of the blind mounted therein, together with the tape and slats supported therefrom.

Figure 2 is a perspective view showing the 15 complete enclosure with the cover member in place therein.

Figure 3 is an elevational view showing the 20 head enclosure supported in a window frame, the same being a somewhat fragmentary view disclosing a mounting bracket customarily used in such an assembly.

Referring to the drawing, it should be stated 25 that certain of the mechanism disclosed in Figure 1, together with Figure 3, is more completely described in the copending Wright and Zay application, Ser. No. 187,622 filed September 29, 1950, and only generally referred to herein. More specifically certain of the details described herein are disclosed in the co-pending application of Robert W. Meyer, Ser. No. 225,501 filed May 10, 30 1951.

In those applications above referred to, the 35 tilting mechanism and cord lock mechanism, together with the combination tilt and head bar used in Venetian blinds and also the main supporting brackets for the head bar are described and referred to in detail. They are only shown in this particular application, in order to illustrate certain features which this application 40 makes possible, and furthermore to additionally disclose the manner of assembly of the disclosures in this invention in a Venetian blind.

Referring at this point particularly to Figure 45 1, there is illustrated a head enclosure generally designated 1 of substantially U-shaped configuration in cross section. The bottom member or main part of the enclosure designated 2 is preferably of concave construction substantially as illustrated and the side members 3 and 4 are 50 of convex construction as respects their relationship to the previously mentioned member 2. This entire U-shaped enclosure member 1 is preferably formed of relatively thin metal or the like and integrally made, whereby the respective upper members 3 and 4 are relatively resilient

transversely, but of substantial rigidity longitudinally.

In Figure 1 there is disclosed the combination head and tilt bar generally designated 5, more completely described in the above mentioned Meyer application, Ser. No. 225,501, the same being provided with the tape designated 6, suitably fastened at its ends to the tape-supporting member 7, said tape in turn depending therefrom. As is usually the case in Venetian blinds the tape 6 includes the necessary ladders 8 thereon in which are supported the slats 9. These slats are generally formed of thin metal or the like and of sufficient width to extend from side to side of the ladder and are adapted in accordance with usual construction to be moved into horizontal and vertical position or positions intermediate the same for regulating light entrance into the room from the window in which the blinds as a whole may be installed.

The above mentioned slats 9 are rolled or otherwise formed so as to present a concave construction in cross section and are therefore relatively stiff both longitudinally and transversely, although being flexible and resilient at the same time.

At the upper ends of the side members 3 and 4 are the downwardly depending cover supporting members 10 and 11 respectively. These cover supporting members 11 are formed so as to provide longitudinally extending grooves, the same being integral with the side members 3 and 4 and formed of the metal from which the sides 3 and 4 and the bottom member 9 are initially rolled.

The grooves 12 and 13 in the cover supporting members 10 and 11 respectively, extend throughout the length of the upright members 3 and 4 and are adapted to support therein a cover designated 14. The cover 14 is preferably a thin piece of metal, and in this instance is shown as being the same width and the same cross sectional curvature as the slat 9. In fact, the cover member 14 is intended to be formed of the same material from which the slats 9 are made. It will therefore be apparent that the width between the grooves 12 and 13 is therefore intended to be substantially the width of the cover member 14, in this case a slat, and therefore a notable saving in cost is effected by availing of such cover member as 14 shown here.

With the foregoing description of the various parts in mind, it will be apparent that the cover member 14 may be inserted in position between the respective side members 3 and 4, and supported in the grooves 12 and 13, by slightly compressing the cover member 14 from edge to edge and then slipping the said member into place. It will be furthermore understood that in the alternative the cover member 14 may be entered into the grooves 12 and 13 by insertion from one end or the other of the enclosure 1, properly aligning the respective edges of the member 14 with the grooves 12 and 13 and thereafter moving the cover member into position so as to completely close the top or normally open portion of the enclosure 1.

Figure 2 illustrates the cover member 14 in position, omitting certain of the operating parts normally used, and the enclosure 1 in which the cover member 14 has been inserted.

In Figure 3 the entire assembly is shown as having been mounted in a window frame, with the usual main supporting brackets 15, only one being shown in this instance, whereby the ends

of the tubular enclosure form have been inserted, thus completely enclosing the mechanism within the enclosure 1.

It should be further noted that the concave construction of the cover 14 permits the rotation of the slat and tape supporting members 7 within the enclosure by reason of its concave construction. The concave construction at the same time does not extend above the highest points of the respective side members 3 and 4, and therefore does not interfere with the insertion of the enclosure and its associated mechanism in a window frame or the like.

It should also be understood that it is contemplated that the said closure member 14 may be used with other types of enclosure members 1, in certain instances, the latter being of wood or the like, but most practically this type of construction is more suitable for enclosures constructed of metal, similar to that disclosed herein.

Furthermore the provision of the cover member 14 adds stiffness and rigidity to the enclosure member 1, when the said cover member 14 is associated therewith in the grooves provided therefor.

In view of the foregoing, it will be apparent that there is herein disclosed a novel form of head enclosure unit, for use in Venetian blinds, which not only adds structural rigidity to the head unit as a whole, but furthermore prevents entrance of dust and foreign matter into the mechanism for operating the Venetian blind.

It should be additionally understood that by reason of the relatively resilient connection of the sides with the bottom member, in view of the preferably integral formation thereof, enables a separation of the upper edges of the sides and thus insertion of the cover member 14 in a somewhat different manner from that heretofore mentioned.

By initially entering one edge of the cover member in one of the grooves in one cover supporting member, and subsequent pressure at the other edge of the member 14, the said member may be snapped into place at its opposite edge in the groove provided therefor. A slight separation of the free edges of the sides is seen to have taken place to effect this action.

As has been previously stated the cover member for the head enclosure of this invention may most conveniently be provided by using a slat or a member corresponding thereto made of the same material as the slats used in the blind itself. It will be apparent that in those cases wherein slots are provided in the slats, the cover member will be provided without those slots, in order to maintain the interior of the enclosure in dust-free condition. In blinds which do not require the lift cords to be passed through slots in the slats or similar openings, an additional slat corresponding in dimensions to the slats therein may be used.

Having thus disclosed and described my invention, what I claim as new and desire to secure by Letters Patent of the United States is:

A Venetian blind comprising a head enclosure consisting of an approximately U-shaped body, said body having an upwardly concaved bottom formed with integral upright front and rear side members, at least one of said side members being of convex form with its convex surface outward, a tilt bar in said enclosure having slat supporting tapes thereon, at least one slat carried by said tapes and said slat being of concavo-convex form in cross section with its con-

vexity generally of the same degree as that of the one convex side previously mentioned so that when the blind is closed in one direction the slat at its convex face will be similar in appearance to and conform with the convexity of said convex side of the enclosure, and a closure for the top of the head enclosure, said closure comprising a slat like that supported by the tape, said closure slat being interlocked at its longitudinal edges with the upper longitudinal edges 10 of the front and rear side member of the head.

RICHARD H. WRIGHT.
